UNITED STATES PATENT OFFICE

148,930

DESIGN FOR A CHILD'S BRICK

Bertram Mark Hickman, London, England

Application January 23, 1946, Serial No. 125,861
In Great Britain July 25, 1945

Term of patent 14 years

(Cl. D34—15)

To all whom it may concern:

Be it known that I, Bertram Mark Hickman, a subject of the King of Great Britain, residing at 657 North Circular Road, London N. W. 2, England, have invented a new, original, and ornamental Design for a Child's Brick, of which the following is a specification, reference being had to the accompanying drawings, forming part thereof; in which

Figures 2 to 5 inclusive are drawn to a scale smaller than that of Fig. 1.

I claim:

The ornamental design for a child's brick, substantially as shown.

BERTRAM MARK HICKMAN.
